UNITED STATES PATENT OFFICE.

GEORGE J. ALTHAM, OF FALL RIVER, MASSACHUSETTS.

VALVE MECHANISM FOR EXPLOSIVE-ENGINES.

SPECIFICATION forming part of Letters Patent No. 712,171, dated October 28, 1902.

Application filed January 3, 1900. Serial No. 271. (No model.)

To all whom it may concern:

Be it known that I, GEORGE J. ALTHAM, of Fall River, in the county of Bristol and State of Massachusetts, have invented certain new 5 and useful Improvements in Valve Mechanism for Explosive-Engines, of which the following is a specification.

This invention relates to engines employing oil, gas, or other hydrocarbon fluid as the 10 source of energy.

The chief object of my invention is to provide improved valve-operating mechanism, such mechanism also comprising or being adapted to coöperate with means for regulating 15 the speed of the engine by controlling the admission of the explosive charges to the working cylinder or cylinders.

According to my invention I employ one 20 valve, preferably a piston-valve, which serves both for the admission of the explosive charges to the working cylinder and also for the admission of the compressed air which is blown through the engine after each working stroke. I cause this valve to be operated only when 25 an impulse-stroke is required. At all other times it remains practically stationary, thereby avoiding vibration and wear of the working parts. I employ a single shaft to operate the aforesaid valve and the exhaust-valve.

30 In order that my invention may be clearly understood and readily carried into effect, I will describe the same fully with reference to the accompanying drawings, in which—

Figure 1 is a front elevation of one example 35 of valve-operating mechanism constructed according to my invention. Fig. 2 is a vertical section of the mechanism, taken through the valve-operating shaft and showing the parts in a different position from that illustrated 40 in Fig. 1. Fig. 3 is a sectional side elevation on the line A B of Fig. 1; and Figs. 4, 5, and 6 are views similar to Fig. 3, showing the parts in different positions. Fig. 7 is a side elevation of my improved valve-operating 45 mechanism applied to a two-cylinder engine, and Fig. 8 is a sectional end view taken on the line C D of Fig. 7. Fig. 9 is a longitudinal section of the aforesaid piston-valve, its casing, and the end of the working cylinder. 50 Figs. 10 and 11 are respectively an elevation and a transverse section of the valve-casing or cylinder detached. Fig. 12 is a detail per-

spective view hereinafter referred to. Fig. 13 is an elevation, partly in section, representing a form of engine with my improvement applied thereto.

Referring first to Figs. 1 to 6, *a* is the valve-operating shaft, which is hollow and is supported in bearings *b*. It is adapted to be driven by any suitable rotating part of the engine through the pinion *c*. A centrifugal governor is arranged at one end of this shaft, which latter is slotted at *d* for the purpose of permitting the ends of the arms *e* of the bell-crank levers carrying the governor-weights 65 to engage with a recess *f* in a spring-controlled spindle *g*, arranged within the shaft. Near its opposite end this spindle is secured, by means of a pin or key *h*, passing through a second slot *i* in the shaft *a*, to a sleeve *j*, capable of sliding longitudinally on the said shaft. (See Fig. 2.) Upon this sleeve is a cam *k*, adapted to engage with the arm *m* of a spring-controlled catch-lever, whose pivot or spindle is mounted in bearings *l*. So long as the speed of the engine is sufficiently high to cause the governor to hold the spindle *g* against the tension of its spring this cam *k* is not brought into contact with the arm *m*, as will be clearly seen on reference to Fig. 2; but when the speed slackens the sleeve is permitted to move along the shaft to a position where the cam thereon 70 will operate the arm *m* so as to trip the lever, this latter position being shown in Fig. 1. The catch-lever has three arms, one of which, 75 *m*, is arranged to come against the cam *k* and another, *n*, is pressed by the spring *o*, by which the lever is controlled. The extremity of the third arm *p* is adapted to extend under the outer end of a spring-controlled lever *q*, 80 (see Figs. 3, 4, and 12,) to which is connected the rod *r* of the aforesaid admission-valve *s*. The arm *p* catches and holds the said lever *q* against the tension of its spring in such a position that this valve *s* opens the working cylinder *u* of the engine to the channel *v*, communicating with a reservoir containing compressed air, the channel *w* affording communication between said cylinder and the chamber containing the charges of combustible 85 fluid being then closed. The lever *q* when not held by the arm *p* is adapted to be actuated by a cam *x*, secured on the valve-operating shaft *a*. This cam *x* (which may be

termed the "valve-cam") is of such a shape and is so disposed angularly with relation to the trip-cam k on the sleeve j that the lever q is held thereby in its normal position at the 5 moment that it is released by the arm p . The position of the parts at such time is shown in Fig. 4. The rotation of the valve-cam then immediately permits the lever q to move under the action of its spring t so as to bring 10 the valve s into its opposite or "charging" position, as will be seen in Fig. 5, and afterward pushes said lever q back to a middle position, in which the valve s closes communication between the cylinder u and both the 15 channel v and the channel w while the "compression" and "impulse" strokes of the working piston take place. The position of the parts toward the end of the compression stroke is shown in Fig. 6. At the end of the 20 impulse-stroke the valve-rod lever is returned by the cam x to its normal position or that position wherein the compressed air is admitted to the cylinder. The arm p of the catch-lever will then reengage the extremity of the 25 valve-lever and hold it in such position until a fresh charging stroke is required, the cam-shaft rotating, pending such requirement, without operating the catch or valve levers, as will be understood from Fig. 3. During 30 the movement of the valve-lever its extremity bears upon an arc-shaped surface y of the arm p , the said arc having a radius equal to the length of the lever q , thereby preventing the arm p moving into the path of the said 35 lever until the latter has returned to its normal position. When a pump is employed to force the combustible fluid into the charge-chamber, I prefer to work the plunger of such pump by a rod z , connected to the ext- 40 tension or lug l on this arm p of the catch-lever. (See Figs. 2, 3, and 12.) In order to insure that the cam k shall engage the arm m of the catch-lever for a time sufficient to trip the same and effect the release of the lever q , I provide on the sleeve j a knife-edged 45 or bevel cam or ridge 2, one side of such cam being approximately perpendicular and the other inclined. This cam 2 is adapted to be engaged by a similarly-shaped roller 3, carried 50 by the wall of the casing 4 that incloses the mechanism. The roller 3 does not touch the sleeve j , and normally it does not touch the cam 2; but when said sleeve is permitted by the governor to move so as to bring the 55 cam k near to or in contact with the arm m the inclined surfaces of the said roller and knife-cam will engage and will thereby draw back the sleeve j to or will retain it in such a position that the cam k will make a good 60 contact with the arm m , and the cam 2 will not be released by the roller 3 until the catch-lever has released the valve-lever q . I prefer to mount the said roller on an arm 5, held in position in a resilient manner by the spring 65 6 or a similar device, so as to permit the said arm to move away from the sleeve, if necessary.

Referring now to Figs. 7 and 8, which illustrate one form of my invention applied to a two-cylinder engine, each cylinder being controlled by a separate valve, it will be seen that the two valve-rods $r r'$ are disposed opposite to each other and connected to valve-levers $q q'$, arranged on either side of the valve-operating shaft a . A single cam x operates the two valve-levers. Two catch-levers are employed, mounted in bearings $l l'$, and two trip-cams $k k'$ are also employed, one for each catch-lever. Each trip-cam is mounted on a separate sleeve $j j'$, one sleeve being arranged on each side of the valve-cam x and both sleeves being actuated by the spindle g in the manner hereinbefore described. The construction of the catch-levers is somewhat different to that illustrated in Figs. 1 to 6. 75 Each catch-lever comprises two arms, one of which, m , (or m'), carries the roller through which it is adapted to be actuated by the trip-cam, the said arm being prolonged in a curve approximately concentric to the cam-shaft and having pivoted to its extremity the rod z (or z') of the pump for forcing the combustible fluid into the charge-chamber. In order that the deflection of the pump-rod in its reciprocating movement may be as slight as 85 possible, it is so arranged that a line joining the pivot of the catch-lever and the point of its connection to the pump-rod is approximately at right angles to the pump-rod itself. The pump operated by the rod z supplies the 90 charging member of the working cylinder whose valve is controlled by the rod r , and the pump operated by the rod z' supplies the charging chamber of the working cylinder which is controlled by the rod r' . The other 95 arm p (or p') of the catch-lever is set off from the arm m , (or m'), is curved to escape the pivot or fulcrum of the other catch-lever, and is then further set off, so that the end of this arm having the arc-shaped surface y (or y') 100 may be in the plane of the valve-lever q (or q'). A compression-spring o , (or o'), bearing against the arm m , (or m'), tends to maintain the catch-lever in its catch position. 105

Referring now to Figs. 9 to 11, the piston-valve s that I prefer to employ for admitting the explosive mixture and the compressed air to the working cylinder u consists of a cylindrical piston or plug working in a fixed casing or cylinder 7, communicating at one 110 end with the channel w , and hence with the chamber containing the charges of combustible fluid, and at the other end with the channel v , and hence with the compressed-air reservoir. At or near the middle of this 115 cylinder 7 are a number of radial perforations 8, opening into an annular chamber 9, communicating with the working cylinder u . When the piston covers these perforations, the working cylinder is closed to both the 120 aforesaid chamber and the compressed-air reservoir. When the piston is moved toward the channel w , compressed air is admitted to the working cylinder, and when it is moved 125

toward the channel *v* the explosive mixture is admitted to the working cylinder. I employ an exhaust-valve of any ordinary construction, operated from the aforesaid valve-5 operating shaft *a* by a cam or eccentric situated in the casing, (marked 15.) As shown in the drawings, I employ antifriction-rollers on the parts of the levers that come in contact with the cams.

10 I claim—

1. A valve mechanism for engines of the character specified, comprising an admission-valve, a constantly-moving actuator, as a cam, means for transmitting motion from 15 said actuator to the valve, a centrifugal governor, a catch controlled by the governor and adapted to be moved thereby to a position to hold said motion-transmitting means out of position to be operated by said actuator, and a trip-cam controlled by the governor for releasing the said motion-transmitting means, whereby the valve is adapted to be held stationary in an inoperative position until a decrease in the speed of the engine necessitates a fresh impulse-stroke and to be then released.

2. A valve mechanism for engines of the character specified, comprising a valve, a centrifugal governor, a catch adapted to normally 30 hold said valve stationary in an inoperative position, a trip-cam controlled by the governor and adapted to operate said catch and release the valve when a decrease in the speed of the engine necessitates a fresh impulse stroke, and means for insuring the proper coöperation of said trip-cam and catch, said means including members having 35 inclined faces, one member being relatively

fixed and the other relatively movable and connected with the trip-cam. 40

3. A valve mechanism for engines of the character specified, comprising a valve, a centrifugal governor, means for operating and controlling the action of the valve, said means comprising a shaft, a sleeve on said 45 shaft connected with the governor and having a cam for tripping the valve-controlling means, and means insuring a proper positioning of said trip-cam, said means comprising a cam mounted on the sleeve and 50 having an inclined face, and a fixed roller having an inclined face adapted to engage said face on the cam and thereby move the sleeve longitudinally on the shaft.

4. A valve mechanism for engines of the character specified, comprising the working cylinder, a cylindrical casing having a port intermediate its ends communicating with the interior of said cylinder, said cylindrical casing communicating at its ends, respectively, with a chamber for containing the working charges for said cylinder, and a reservoir for compressed air or other fluid for blowing through the engine, a piston or plug working in said casing and adapted to close 65 said port or to lie on one or the other side thereof, and means for actuating said piston or plug, whereby a single valve performs the functions of an admission-valve and a blow-through valve. 70

In testimony whereof I have affixed my signature in presence of two witnesses.

GEORGE J. ALTHAM.
